DESIGN FOR A STRAW DISPENSING JAR

Benjamin M. Oswell, Los Angeles, Calif.

Application March 12, 1938, Serial No. 75,776

Term of patent 14 years

To all whom it may concern:

Be it known, that I, Benjamin M. Oswell, a citizen of the United States, residing at Los Angeles, in the county of Los Angeles and State of California, have invented a new, original, and ornamental Design for a Straw Dispensing Jar, of which the following is a specification, reference being had to the accompanying drawing, forming a part thereof.

Fig. 1 is a side elevational view of a straw dispensing jar, showing my new design.

Fig. 2 is a vertical section taken lengthwise through the center of the jar.

Fig. 3 is a horizontal section taken on the line 3—3 of Fig. 1.

My design is characterized by a jar of the contour shown in which the outer surface of the jar is continuously fluted vertically over a large central area thereof, said jar being provided with an upper annular area having an annular bead, and an annular base area having an annular bead, the base area being substantially twice that of the upper area.

I claim:

The ornamental design for a straw dispensing jar, as shown and described.

BENJAMIN M. OSWELL.
